UNITED STATES PATENT OFFICE.

HOWARD CHAUNCEY WHITNEY, OF ALBANY, NEW YORK.

COMBINED BLOTTING-PAD AND MEMORANDUM-BOOK.

SPECIFICATION forming part of Letters Patent No. 337,101, dated March 2, 1886.

Application filed December 14, 1885. Serial No. 185,501. (No model.)

To all whom it may concern:

Be it known that I, HOWARD CHAUNCEY WHITNEY, a citizen of the United States, residing at Albany, in the county of Albany and State of New York, have invented certain new and useful Improvements in a Combined Blotting-Pad and Memorandum-Book; and I do hereby declare the following to be a full, clear, and exact description of the invention, such as will enable others skilled in the art to which it appertains to make and use the same.

My invention relates to certain new and useful improvements in combination blotting-pads and memorandum books, and is designed as an improvement upon the device heretofore patented to me under date of October 27, 1885, and numbered 329,348.

My present invention is illustrated in the accompanying drawings, wherein Figure 1 represents a plan view thereof. Fig. 2 represents a longitudinal section on the line 2 2 of Fig. 1, and Fig. 3 represents a cross-section on the line 3 3 of Fig. 1.

Similar letters of reference indicate similar parts throughout the several views.

d indicates a base consisting, preferably, of pasteboard, and provided with the triangular pockets *b*, for the reception and retention of blotting-paper, thereby forming upon one portion of the said base *d* a blotting-pad of a well-known type. The remaining portion of the base forms one of the covers of the memorandum-book *a*, which is bound in with it and permanently a part thereof.

As thus constructed, my invention, while presenting the advantages of its predecessor, above referred to, may be produced more economically by reason of the saving in stock and labor incident to the preparation of the

retaining pocket for the book-cover employed in my said former device. There is, moreover, no danger of accidental displacement of the book from the pad, the two being attached to each other in such manner as to be constantly associated for the combined use, as an article of manufacture, for which they are designed.

In the manufacture of my device I preferably bind the base *d* in with the book at the time of making the latter, afterward applying the angle-pockets, and finishing by inserting the blotting-pads. In some instances, however, I may effect the permanent union between the book and base *d* by other means than that described, as will be readily understood. Thus it may be sewed, pasted, or otherwise fixedly and securely fastened to the base, without being united thereto by what is technically known as "binding." I prefer the latter method, however, because of its greater security and the better appearance of the work produced.

Having thus described my invention, what I claim, and desire to secure by Letters Patent, is—

As a new article of manufacture, a base-board provided at one end with means for retaining sheets of blotting-paper and at its other end with a book, to which it is permanently attached, forming a continuation of one of the book-covers, substantially as described.

In testimony whereof I affix my signature in presence of two witnesses.

HOWARD CHAUNCEY WHITNEY.
